DESIGN FOR A TOY DUCK

Edward McCandlish, Plymouth, Mich.

Application January 25, 1935, Serial No. 55,048

Term of patent 7 years

To all whom it may concern:

Be it known that I, Edward McCandlish, a citizen of the United States, residing at Plymouth, in the county of Wayne and State of Michigan, have invented a new, original, and ornamental Design for a Toy Duck, of which the following is a specification, reference being had to the accompanying drawing, forming part thereof.

Figure 1 is a side view of a toy duck, showing my new design; Figure 2 is a front view; and Figure 3 is a top plan.

I claim:

The ornamental design for a toy duck, as shown.

EDWARD McCANDLISH.
